WALTER W. WEISER, OF CHICAGO, AND GUSTAF A. FORSBERG, OF CICERO, ILLINOIS.

MOTOR FOR PLAYER PIANOS.

Application filed March 15, 1922. Serial No. 543,897.

To all whom it may concern:

Be it known that we, WALTER W. WEISER and GUSTAF A. FORSBERG, citizens of the United States, residing, respectively, at Chicago and Cicero, in the county of Cook and State of Illinois, having jointly invented certain new and useful Improvements in Motors for Player Pianos, do hereby declare that the following is a full, clear, and exact 10 description of the same.

In the accompanying drawings, which illustrate embodiments of the several features of our invention, Fig. 1 is a perspective view in elevation with certain parts in section; Fig. 2 is a bottom plan view with the shelf omitted for clearness of illustration; Fig. 3 is a transverse vertical sectional view on the line 3—3 in Fig. 1; Fig. 4 is a similar view on the line 4—4 in Fig. 1 with the channel board shown partly in section and partly in elevation for clearness of illustration; Fig. 5 is a detail vertical sectional view on the line 5—5 in Fig. 4; Fig. 6 is a detail sectional view on the line 6—6 of Fig. 7 taken 25 through the rotating valve; Fig. 7 is a detail view in elevation of the inner or ported face of the valve, and Fig. 8 is a view in side elevation of the center-bar.

Our invention relates to various features 30 of vacuum motors for operating the usual transmission for the forward and rear drive of the take-up spool and the feed-roll chucks respectively to roll and reroll the music sheets in player-pianos; its primary object is 35 to provide an organization for operating a six-point motor by a single valve, a further object being to provide push-connections between the motor shaft and all the motor pneumatics, and other objects and advantages being apparent from the disclosure of 40 the invention.

In the drawings the reference letter A indicates the usual spool-box shelf in the piano case upon which the motor is customarily 45 mounted adjacent the spool-box (not shown) in which the take-up spool and the feed-roll chucks are mounted with the usual transmission (not shown) to which motion is imparted from the crankshaft B of the motor 50 by the joint b to roll the music sheet forward on the spool and re-roll it on its roll between the chucks, it being understood that the crankshaft of the motor turns always in the same direction and that the direction of 55 movement of the music sheet is governed by

the shifting of the transmission by the usual re-roll lever.

The motor frame comprises the opposite standard C and channel-board D with the center-bar E between them, these parts being rigidly connected by suitable tie-rods e and fastened to the shelf A by screws passing through a foot-piece c on the standard and a lateral block D' on the channel-board. The standard and block are provided with 60 bearings having packing-glands for the shaft B, that in the block being covered by a closure cap D² screwed thereto to prevent air leakage therethrough. The channel-board is provided on its inner face with a 65 circular valve-seat D³, and a horizontal exhaust-channel D⁴ extends through the center of this seat and through the channel-board and its block co-axially with the shaft B and communicates with a vertical channel 70 D⁵ in the block with which one end of the motor-exhaust tube D⁶ connects, its other end being connected in the usual manner to the foot-operated exhaust bellows (not shown). 75

The center-bar E carries six bellows F, G, H, K, M, and N, forming the motor pneumatics, and arranged in opposite pairs, and whose power is applied at three points to the crank-shaft. The center-bar E is provided with six longitudinal air-channels F', G', H', K', M' and N', all of the same length and disposed in vertical alinement one above the other, and respectively communicating by lateral ports f, g, h, k, m, and n with the bellows or pneumatics F, G, H, K, M and N, the three ports for the front bellows F, G and H opening through the front side of the center-piece, and the three ports for the rear bellows K, M, and N opening 90 through its rear side as shown in Fig. 8. In practice we prefer to standardize the bellows so that any one of them when mounted on the center-bar will communicate with any of the lateral ports, and for this purpose 95 the rear wall of each bellows that is attached to the bar E is provided with an elongated slot, as indicated at x in Fig. 3, which is of sufficient length to extend across the row of air-channels and register with any of the lateral ports, so that in assembling the bellows on the bar E it is not necessary to 100 select any particular one for any particular port, as the slot in each will co-operate with any port. The channel-board D is provided 105 110

with six curved air-channels f' , g' , h' , k' , m' , and n' , respectively communicating with the outer or open ends of the horizontal air-channels F' , G' , H' , K' , M' and N' as shown in Fig. 4, and arranged in two sets of three each on opposite sides of the median line of the block in which the bar E is centered, the channels of the bellows of each pair being on opposite sides of this line. The lower ends of the channels in the board D are grouped in a circle whose center is coincident with the axis of the exhaust-channel D^4 and whose diameter is less than that of the valve-seat D^3 , and are provided respectively with inwardly directed lateral ports or openings f^2 , g^2 , h^2 , k^2 , m^2 , and n^2 , extending through the valve-seat and terminating in the same vertical plane at its front face. These ports are spaced apart equally and concentrically with the exhaust-channel D^4 , and are arranged in opposite pairs corresponding with the pairings of their associated bellows. The communicating air-channels in the center-bar and channel-board with their respective ports afford air-passages between the motor pneumatics and the single valve-seat.

A rotary valve O for admitting and exhausting air to and from the motor pneumatics is connected to the shaft by a set-collar o on the shaft and carrying an angular arm o' which engages in a slot o^2 in the body of the valve so that it rotates in unison with the shaft. The valve is formed by a block which is cup-shaped in cross-sectional contour and its rim is of the same diameter as the seat D^3 against which it is snugly but revolvably held by a light spring o^3 coiled around the shaft and reacting between the fixed collar o and the head of the valve, which latter is provided with a passage for the shaft B having a suitable packing gland to prevent air leakage, the shaft being held against longitudinal displacement by the collar o and a set-collar b' on its other end abutting against the standard C . The valve-faces O' are flush with the rim of the valve and on diametrically opposite sides of its center, and act to successively close the opposite pairs of lateral ports of the valve-seat as the valve is rotated. The interior of the valve is provided with a motor exhaust port or chamber O^2 which is recessed into its body and is substantially sector-shaped in outline with more or less curved or rounded sides; its inner or base portion is at the center of the valve in registry with the open end of the exhaust-channel D^4 in the block D , and its peripheral or outer portion is flared circumferentially and of sufficient area to register with any adjacent pair of the bellows ports f^2 , g^2 , h^2 , k^2 , m^2 and n^2 of the valve-seat to exhaust the air from the corresponding bellows. The valve is also provided with an air ingress or supply port O^3

by which outside air is admitted to the motor pneumatics; this port passes through the portion of the valve-body which is on the side of the valve-faces opposite to the exhaust-port O^2 , and is separated from the latter port by an extension o^4 of the valve-faces. The supply port O^3 extends circumferentially to register with any adjacent pair of the bellows ports of the valve-seat to admit outside air to the corresponding bellows; in practice the outer end of this inlet port O^3 is divided by a portion of the valve-head extending across its center to strengthen the structure of the valve. The valve rotates in the direction of the arrows, and its ports are so proportioned and related to the bellows ports of its seat that when the exhaust chamber O^2 registers with any adjacent pair of these ports, as g^2 and n^2 in the position of the valve shown in Fig. 3, to create partial vacuum in the corresponding bellows, as in this figure in the bellows G and N , the air ingress or supply port O^3 will register with the two seat-ports corresponding to the opposite bellows, as here h^2 and m^2 to supply outside air to the bellows H and M , and the valve-seats O' will close the remaining bellows ports of the seat, as here shown f^2 and k^2 to shut off the bellows F and K , so that there is no leakage of air. As the valve rotates the air is exhausted from one of each pair of bellows and enters the other as the valve-faces begin to uncover the bellows ports in the valve-seat corresponding to that particular pair. Each pair of bellows is connected to a crank of the shaft, there being three cranks arranged one-third of a circle apart or at equal angles of 120° , and thus a very uniform turning stress or force on the shaft is obtained; at each half revolution of any crank one bellows of its pair is collapsed by the outside air pressure and at the next half revolution the other bellows of its pair is collapsed by similar pressure. The single valve serves both the front and rear sets of pneumatics of the six-point motor, and is timed so that its opposite faces O' will close the seat-ports of each pair of pneumatics when the crank of that pair is on its dead center, and its exhaust and supply ports will synchronously register respectively with the opposite pairs of seat-ports to govern the air-exhaust and ingress of the corresponding bellows when their cranks are off their dead centers. As shown, when any pair of pneumatics is thus closed by this valve, the air is synchronously exhausted through its exhaust-port O^2 from two pneumatics of the other pairs on opposite sides of the center-bar to allow them to collapse under pressure of the outside air to actuate the shaft, and is admitted through its supply port O^3 to the other two pneumatics of the other pairs to expand them synchronously. Thus the suction through the single

port O^2 simultaneously exhausts two pneumatics of the opposite sets to allow them to collapse under the pressure of the outside air, and so two pneumatics act at all times to turn the shaft. As all the channels in the center-bar E are of the same length the same amount of energy or power is required on alternate sides to create the vacuum in the several pneumatics. The torque established 10 on the shaft is smooth and powerful.

The moving walls of the bellows are connected to the shaft by open-end linkage P; this wall of each bellows carries a depending loop f^3, g^3, h^3, k^3, m^3 and n^3 , respectively, 15 and a link P is interposed between each loop and its opposite crank on the shaft, being provided with open-end slots p at its ends which receive the opposed loop and crank.

By this construction the stress of the shaft 20 on each bellows to expand it and the stress of all the bellows on the shaft when they collapse to turn it is applied by a push; in short all links are of the push type only, so that there is no play between the parts and 25 the operation of the motor is noiseless. The opposite bellows of each pair are connected by a contractile spring S suitably attached by eyes s to their moving walls, which tends to draw these walls toward each other and 30 keep the opposed bellows-loops and cranks of the shaft seated in the bases of the slots of their links to take up wear and eliminate all lost motion or play. There being three springs associated with the three cranks of 35 the shaft when one spring begins to be extended the other two begin to contract so that the spring action or opposition to the rotation of the shaft by the collapse of the bellows is balanced or neutralized.

40 When the foot-pedals are operated to produce vacuum in the equalizers in the usual manner, air will be sucked through the exhaust tube D^6 from the motor pneumatics or bellows whose valve-seat ports are in register with the exhaust chamber of the valve, and outside air will flow into the opposite pneumatics through the air ingress port of the valve, while the other pair of pneumatics will be sealed by the valve-faces closing 45 their seat-ports. The six bellows will thus successively collapse and expand through the function of a single valve admitting and exhausting air to and from them to turn the crank-shaft to drive the transmission, which 50 according to its position operates either the take-up spool or the feed-roll chucks to roll or reroll the music sheet.

We claim:

1. In a device of the class described, a 55 vacuum motor comprising a frame, six bellows arranged in opposite pairs on the frame, air-channels in the frame communicating with the bellows and terminating in ports arranged in the same plane, a crank- 60 shaft connected to the bellows, and a sin-

gle valve on the shaft constructed to close the ports of any pair of bellows and to govern the air exhaust and ingress of the other pairs of bellows.

2. In a device of the class described, a 70 vacuum motor comprising a frame, having an exhaust passage, six bellows arranged in opposite pairs on the frame, air-channels in the frame communicating with the bellows and terminating in ports arranged in the 75 same plane and spaced around the exhaust passage, a crank-shaft connected to the bellows, and a single valve on the shaft having valve-faces constructed to close the ports of any pair of bellows and having exhaust and 80 suction ports constructed to govern the air exhaust and ingress of the other pairs of bellows.

3. In a device of the class described, a 85 vacuum motor comprising a frame having a valve-seat provided with a central exhaust passage and six ports arranged in opposite pairs around the passage, six bellows arranged in opposite pairs on the frame, air-channels in the frame communicating with 90 the bellows and with the ports, a crank-shaft having three cranks, connections between each pair of bellows and a crank, and a single valve on the shaft constructed with opposite valve-faces to close the opposite 95 ports of any pair of bellows and with exhaust and suction ports on opposite sides of the valve-faces to govern the exhaust and ingress of air from and to the other pairs of bellows.

4. In a device of the class described, a 100 motor frame comprising a center-bar having a plurality of superposed channels of equal length and lateral ports therefor on its front and rear faces, front and rear sets of bellows on the bar arranged in three opposite pairs and communicating with said ports, a 105 shaft mounted in the frame having a crank-connection with each pair of bellows, and a single valve on the shaft constructed to close the channels of one pair of bellows when its crank is on a dead center and to admit and exhaust air to and from opposite bellows of the other pairs.

5. In a device of the class described, a 110 frame having a valve-seat provided with an exhaust passage, six bellows on the frame arranged in opposite pairs, the frame having air-channels communicating with the bellows and terminating in lateral ports arranged in opposite pairs around the exhaust passage, a shaft having a crank connected to each pair of bellows, and a single valve on the shaft having opposite valve-faces constructed to close an opposite pair 115 of ports and having exhaust and supply ports each constructed to register with an adjacent pair of ports.

6. In a device of the class described, a 120 frame comprising a longitudinal center-bar 125

and a vertical channel-board having six registering air-channels, bellows on the bar in communication with the channels therein, the channel-board having an exhaust passage and lateral ports for the air-channels disposed around the exhaust passage in opposite pairs, a crank-shaft connected to the bellows, and a single valve on the shaft having opposite valve-faces constructed to close an opposite pair of ports and having exhaust and supply ports on opposite sides of its valve-faces, each of said ports extending circumferentially of the valve to register with an adjacent pair of ports.

7. In a device of the class described, a motor frame comprising a center-bar having a plurality of superposed horizontal air-channels and lateral ports therefor in its front and rear faces, and bellows having passages in their rear walls constructed to register with any of the ports in the center-bar.

8. In a device of the class described, a motor frame comprising a center-bar having a plurality of superposed horizontal air-channels and lateral ports therefor in its front and rear faces, and bellows having elongated slots in their rear walls constructed to register with any of the ports in the center-bar.

9. In a device of the class described, a motor frame having a channeled center-bar provided with front and rear ports, front

and rear sets of bellows arranged on the bar in opposite pairs in communication with the front and rear ports respectively, a crank-shaft mounted in the frame and having its cranks offset at equal angles between the pairs of bellows, and push-links connecting each crank with a pair of bellows.

10. In a device of the class described, a motor frame having a channeled center-bar provided with front and rear ports, bellows arranged on the bar in opposite pairs, in communication with the front and rear ports respectively, a crank-shaft mounted in the frame and having its cranks arranged between the pairs of bellows, and open-end links connecting each crank with its bellows.

11. In a device of the class described, a motor frame having a channeled center-bar provided with front and rear ports, bellows arranged on the bar in opposite pairs in communication with the front and rear ports respectively, a crank-shaft mounted in the frame and having its cranks arranged between the pairs of bellows, open-end links connecting each crank with its bellows, and a retractile spring connecting the movable walls of each pair of bellows.

In testimony whereof we affix our signatures.

WALTER W. WEISER.
GUSTAF A. FORSBERG.
